UNITED STATES PATENT OFFICE.

EDWARD B. HOUGH, OF PROVIDENCE, RHODE ISLAND.

MATCH BOX.

Application filed December 9, 1926. Serial No. 153,487.

The invention relates to match boxes of the type usually carried around in the pocket and used to hold a package of matches, and more particularly to a construction of a match box of this type by which a match may be struck and ignited easily, surely and safely.

According to the invention a match box is provided which may comprise a pair of covers in one or both of which may be disposed a package or book of matches of the usual construction. In the case of a match book or package in each cover, the match box is so arranged that, in order to light a match it may be placed with the head between the striking surfaces of the match books and the match given a quick pull out of the box.

In the drawings accompanying and forming part of this specification, a practical commercial embodiment of the invention is disclosed, but as such illustration is primarily for purposes of disclosure, it will be understood that the structure may be modified in various respects without departure from the broad spirit and scope of the invention as hereinafter defined and claimed.

In the drawings:

Fig. 1 is a perspective view of the match box in closed position;

Fig. 2 is a longitudinal section taken through the match box with the covers in open position;

Fig. 3 shows the match box in open position, one of the cover members of the match box being shown in plan view, and the other cover member being shown foreshortened;

Fig. 4 is a perspective showing the covers with a match between the scratching surfaces, the match being in position for quickly pulling out of the box to ignite it; and

Fig. 5 is a detail showing a section through the hinge.

In the following description and in the claims parts will be identified by specific names for convenience, but they are intended to be as generic in their application to similar parts as the art will permit.

Referring now to the drawing, the match box may comprise a pair of cover members 1 and 2, the base cover member 1 comprising a bottom wall 3, a front wall 4, a back wall 5 and side walls 6. The shape is generally rectangular with the front and back walls rounding into the bottom wall. The cover is made slightly deeper at the back end, the depth decreasing uniformly toward the front end.

An angle member 8 is provided extending across the width of the box and soldered or otherwise secured in the position shown in Fig. 2. This member may have a hole 9 for a purpose hereinafter described more in detail. The cover may furthermore be provided with a plurality of leaf springs 10 to hold the match book 11 in the cover. Each side wall 6 may furthermore be provided with a notch 12 which is disposed at the end of the striking surface 14 of the match book in the cover. The top cover 2 has substantially the same construction as the base cover. In place of the angle member, however, the top cover 2 is provided with a pin 15 suitably secured to the cover and which fits within the hole 9 when the match box is in closed position to effectively prevent relative lateral movement between the covers.

The cover members are hingedly connected together at their back walls by a hinge construction having a spring built therein to continually urge the covers into closed relation. This hinge, a detail of which is shown in Fig. 5, may be made up of interfitting knuckles secured to the covers, alternate knuckles 17 and 18 of one cover interfitting alternate knuckles 19 and 20 on the other. A pintle wire may be provided having two sections 21 and 22, each section having a flattened portion. A spring member 23 is provided being secured at one end against the flat portion of one pintle section 21 and being securely clamped by the end knuckle 17, the other end of the spring 23 being secured between the flat portion on the other pintle section 22 and a hinge knuckle 20 on the other cover.

It is obvious that this match box may be used with different forms of match books or match packages. For purposes of illustrating the invention a single form of match book will be described. This match book 11 is the most commonly used and comprises a plurality of sheets of paper board partially cut to form matches 25, the sheets being fastened between the back cover 26 of the match book and the striking member 14 by a fastener 24. The striking member 14 is provided with striking material to provide a striking surface for igniting the matches in the well known manner. In order to hold the match book in the cover the back 26 may be torn and inserted under the leaf springs 110 as shown in Fig. 3.

When it is desired to ignite a match, the

match box may be opened and a match 25 broken off from the book in the usual manner. The match is then placed in the position shown in Fig. 4 with its head between 5 the striking surfaces 14 of the match books with the end of the match protruding. The match is then pulled out with a jerk, the scraping of the match head on the striking surfaces insuring quick and certain ignition 10 of the match.

This construction insures that the matches are not only easily lighted without the liability of breaking the cardboard shank of the match, but igniting the remaining matches 15 is positively prevented since, when the match box is in the closed position shown in Fig. 4, it is impossible for sparks to fly or the wind to blow the flame from the ignited match to cause the remaining matches to ignite. The 20 continual urging of the covers into closed relation by the spring hinge not only facilitates and insures closure of the box after using but facilitates using the box in its intended way and reduces the possibility of 25 using the box in other and unsafe ways. Furthermore, the construction is such that the case may be inexpensively made and yet it will stand up in use and give faithful service. There are no parts to break or get out 30 of order, and the match box is simple to operate and the matches may be ignited with great certainty and safety.

While certain novel features of the invention have been shown and described and have 35 been pointed out in the annexed claims, it will be understood that various omissions, substitutions and changes in the forms and details of the device illustrated and in its operation may be made by those skilled in the 40 art without departing from the spirit of the invention.

Having thus described my invention, I claim:

1. In combination, a match box comprising 45 cover members, a spring hinge connecting said cover members and yieldingly urging them into closed relation, a book of matches having a striking strip and disposed in each of said cover members, and means whereby a match may be held with its head between the striking strips of said books and pulled out of the box to light said match.

2. A match box comprising cover members each having a bottom wall and side and 55 ends walls, hinge means connecting said cover members at the back end walls thereof each cover member being adapted to hold a package of matches in said cover member, a side wall of each cover member having a notch disposed at the end of the striking surface of said package, whereby a match may be held with its head between the striking surfaces of said packages and pulled out to light said match.

65 3. A match box comprising cover members

each having a bottom wall and side and end walls, hinge means connecting said cover members at the back end walls thereof, each cover member having spring leaves adapted to engage over the cover of a book of matches 70 to hold said book in said cover member, said side walls of each cover member having notches at the ends of the striking surfaces of said books whereby a match may be held with its head between the striking surfaces 75 of said books and pulled out to light said match.

4. In combination, a match box comprising 80 cover members each having a body with a side wall having a notch, a package of matches and a striking member in each cover, each striking member having one end disposed at its respective notch and extending away therefrom, said striking members being disposed adjacent each other when the 85 box is closed, whereby a match may be inserted between said striking members with its shank protruding through said notches so that it may be pulled out of the box.

5. In combination, a match box comprising 90 a body member and a unitary cover member substantially completely closing the box, a spring hinge connecting said members, a plurality of matches disposed in said body member, there being a striking surface carried by 95 said body member and a cooperating sliding surface carried by said cover member opposite said striking surface, whereby said spring hinge yieldingly urges said members into closed relation and allows a match to be 100 placed with its head between said surfaces and with its shank protruding from said box so that the match may be pulled out to light the match.

6. In combination, a match box comprising 105 a body having an upstanding wall with a restricted opening therein, a plurality of matches disposed in said body, there being a striking surface carried by said body, said striking surface having one end adjoining said opening and extending away therefrom, a unitary cover separably connected to said body and substantially completely closing the box, there being a sliding surface carried by said cover opposite said striking surface, whereby a match may be placed with its head between said surfaces and with its shank protruding through said opening so 110 that it may be pulled out of said box to light the match, said opening being just large enough to allow said match to be conveniently lighted in the manner aforesaid.

7. In combination, a match box comprising 115 a body having a substantially rectangular bottom and upstanding front, back and side walls, a unitary cover connected at said back wall and substantially completely closing said box, a side wall having a small notch therein near said front wall, a book of 120 matches having a striking surface disposed 125 therein near said front wall, a book of 130

in said body with said striking surface extending parallel to said front wall and bottom and extending away from said notch, there being a sliding surface carried by said

5 cover member opposite said striking surface, whereby a match may be placed with its head between said surfaces and with its shank protruding through said notch so that it may be

pulled out of said box to light the match, said notch being just large enough to allow said 10 match to be conveniently lighted in the manner aforesaid.

In testimony whereof I have hereunto set my hand.

EDWARD B. HOUGH.
